(57) **CLAIM**

The ornamental design for a multi player adapter for video game, as shown and described.

DESCRIPTION

FIG. 1 is a perspective view of the multi player adapter for video game according to the present invention.

FIG. 2 is a front view of the multi player adapter for video game of FIG. 1.

FIG. 3 is a rear view of the multi player adapter for video game of FIG. 1.

FIG. 4 is a right side view of the multi player adapter for video game of FIG. 1.

FIG. 5 is a left side view of the multi player adapter for video game of FIG. 1.

FIG. 6 is a top view of the multi player adapter for video game of FIG. 1.

FIG. 7 is a bottom side view of the multi player adapter for video game of FIG. 1; and,

FIG. 8 is an alternate bottom view with cord in alternate position.

The broken lines, which define the boundary of the claimed design, form no part of thereof. The broken lines environmental are for illustrative purpose only and form no part of the claimed design.
